UNITED STATES PATENT OFFICE

GEORGE SAKIER, OF NEW YORK, N. Y., ASSIGNOR TO FOSTORIA GLASS CO., OF MOUNDSVILLE, WEST VIRGINIA

DESIGN FOR A GOBLET

Application filed November 15, 1929. Serial No. 33,450. Term of patent 14 years.

To all whom it may concern:

Be it known that I, GEORGE SAKIER, a citizen of the United States, residing at New York, in the county of New York and State of New York, have invented a new, original, and ornamental Design for Goblet, of which the following is a specification, reference being had to the accompanying drawing, forming part thereof.

Figure 1 is a side elevational view of a goblet; and

Figure 2 is a perspective view of a goblet, showing my new design.

I claim:

The ornamental design for a goblet, as shown.

GEORGE SAKIER.
